FASHIONED FABRIC, HOSIERY, AND
METHOD OF PRODUCTION

Sterling C. Mack, Bangor, Pa.; said Sterling C. Mack and Donald C. Mack, administrator of said Sterling C. Mack, deceased, assignors to Julius Kayser & Co., New York, N. Y., a corporation of New York

Application September 12, 1946, Serial No. 696,445

13 Claims. (Cl. 66—187)

1

My invention is an improved method of narrowing and fashioning knit fabrics and the product thereof, which are particularly suitable for use as blanks for hosiery.

In practicing my invention, a web composed of loops arranged in regular wales and courses may be knit in any usual manner, and in accordance with my invention is narrowed coursewise by overlapping loops of numerous pairs of adjoining wales so as to form a substantially straight coursewise row of adjoining "marks" each composed of a pair of overlapped loops; the "mark" centers being spaced coursewise from one another substantially the same distance that the centers of individual loops were originally spaced from one another. The loops of each pair are held overlapped and the pairs are positioned in proximate, juxtaposed relation to one another by drawing a row of holding loops simultaneously through the pairs of gathered loops, thereby materially reducing the length of the course without appreciably puckering the adjacent web area. Knitting may be thereafter continued in any usual manner to form a further web section, such as a foot section, or to provide raveling courses or seaming courses if the narrowing is required at a terminal of the web, as, for instance, at the terminals of heel tabs or at the point of the toe of a stocking blank.

My invention may be conveniently practiced on a conventional full-fashioned knitting machine having a row or bank of en masse movable knitting needles and narrowing combs comprising groups of points movable coursewise into alignment with needles and lengthwise of the needles to lift loops therefrom or deposit loops thereon.

In practicing my invention on such a machine, a comb containing a group of narrowing points is shifted coursewise step by step along the bank of knitting needles and in the same direction into alignment with looped knitting needles so that each successive coursewise movement to the comb brings its leading point into alignment with a different looped needle. Between each coursewise movement, the points are dipped and elevated to reciprocate them along the lengths of the needles and lift loops from the needles by one reciprocation and deposit loops on the needles by the next reciprocation of the points. As a loop is lifted from each new needle, the "marks" formed by the previous overlapping of loops are simultaneously lifted from their needles and all of the lifted loops are simultaneously shifted coursewise one needle and redeposited so that the single loop on the end point is deposited on a needle already containing

2

a loop and the overlapped loops of the remaining points are deposited on needles which were emptied in the previous loop lifting operation.

Consequently two more loops are lifted by the 5 points after a shift than were deposited by the points immediately before that shift, viz., after the next preceding shift, and the number of needles from which loops are successively lifted by the points vary in an arithmetical progression, 10 viz., one needle, two needles, three needles, four needles, etc.

The principles and characteristic features of my 15 invention, and the manner of practicing my improved method, and of making, constructing and using my improved fabric will further appear from the accompanying drawings and the following description explaining the best mode in which I have contemplated applying such principles.

In the drawings, Fig. 1 is a somewhat diagrammatic elevation of a single unit stocking embodying my invention; Fig. 2 illustrates diagrammatically the shaping of the heel portion of a single unit hosiery blank by the coursewise narrowing of such blank in accordance with my invention; Fig. 3 is a fragmentary diagrammatic plan view of a foot section of a single unit hosiery blank from which the stocking of Fig. 1 was made; Fig. 4 is a diagrammatic plan view of the heel tabs and adjacent portion of a leg blank for making a two-unit stocking; Fig. 5 is a key to the 20 symbols used in Fig. 6 to indicate the numbers of loops on the respective needles; Fig. 6 illustrates diagrammatically part of a row of knitting needles arranged in a conventionally operable bar and a group of narrowing points and indicates the lifting, 25 coursewise shifting, and deposit of yarn loops on such needles in the practice of my invention; Figs. 7 to 12 illustrate diagrammatically the approximate positions the loops of the narrowed course would occupy if the needles were withdrawn from the loops after the various narrowing 30 steps indicated in Fig. 6; and Fig. 13 illustrates diagrammatically the narrowed courses and adjacent courses of the blanks of Figs. 1 to 4 inclusive.

45 Since my invention is of primary utility in the knitting of hosiery blanks and in connection with the fashioning of heel and toe sections of such blanks, I have illustrated my invention in connection with the making of, and as embodied in, 50 full-fashioned hosiery, which may be knit by the single carrier system or three carrier system and generally in any of the well-known ways for manufacturing hosiery of the single unit type or of the multiple unit type, as modified by the narrowing of my invention. In Figs. 1-3 of the

drawing I have illustrated the embodiment of my invention in a single unit stocking having a fashioned leg section 1, a reenforced heel section 2, a reenforced sole section 3, and a reenforced toe section 4, and in Fig. 4 I have illustrated the embodiment of my invention in the terminal portions of the heel tabs of a leg blank which is to be topped onto a footer machine for making a foot section of a two unit stocking.

The blanks for single unit stockings may be conveniently knitted on conventional full-fashioned knitting machines having attachments for widening out and reenforcing portions 5 of the blank to form a heel pocket, as described, for example, in Letters Patent of the United States Nos. 2,298,302 or 2,402,200. Any other suitable method of widening out the blank to form a heel portion may be employed. When a single unit blank has been widened out to the maximum width desired, at, say, the point 6, Fig. 2, a number of courses of such width are knitted sufficient to provide the requisite fabric for a heel pocket. Such number of courses required will, of course, vary widely with the size and type of the stocking.

It has been usual practice to gradually taper inward the widened out heel sections by narrowings forming rows of marks extending walewise of the fabric and parallel with the selvedge edges thereof, thereby incorporating in the instep section a series of courses greatly in excess of those required by the contour of the human foot and tending to cause wrinkling at the instep when the stocking is worn.

In accordance with my invention the widened out heel portion is knit its maximum width for a suitable length and is then abruptly narrowed along a somewhat loose terminal course 25 by narrowings forming rows of marks extending coursewise, and along substantially straight lines extending substantially from the selvage edges on the opposite sides of the blank inward to the inner edges of the reenforced heel area.

This abrupt narrowing of the terminal course 25 curves the widened out heel portion from the shape indicated approximately by the full side line of Fig. 2 to the shape indicated approximately by the curved dash line of Fig. 2 and curves the selvage wales sharply inward and curves the inner wales to a progressively diminishing degree.

When the loose terminal course 25 is sufficiently narrowed, a new course or holding course is interknit therewith and the knitting of the foot continued in the usual manner until the loose terminal course 25a of the toe is reached. This is narrowed in the same manner as the course 25 and finished off by a finishing course or courses 26a and any desired raveling courses or seaming courses.

Two unit stockings knit in any usual manner may have my invention embodied in the toes thereof in the same manner as in single unit stockings and in the terminal courses of the heel tabs as indicated in Fig. 4, wherein 25b indicates narrowed loose courses at the ends of the heel tabs and 25b indicates holding courses similar to the courses 25 and 26 and effecting a fashioning and curving of the selvages and wales similar to that in the reenforced widened heel section of Fig. 2.

The fashioning of knit fabric in accordance with my invention by narrowing a course, such as 25, 25a or 25b, is diagrammatically illustrated in Figs. 5 to 14, inclusive.

As indicated diagrammatically in these figures

of the drawings, after a web has been knit by means of an en masse movable bank of needles 10, 11, 12, 13, 14, 15, 16, 17, 18, 19, . . . of a full-fashioned knitting machine to a point where narrowing is desired or required, and the loops a, b, c, d, e, f, g, h, i, j, . . . forming part of the fell row of loops of the fabric are on the respective needles 10 to 19 . . . , inclusive, as shown in row A of Fig. 6, and the loops are disposed as in

Fig. 7, the course is narrowed by means of a series of narrowing points 20, 21, 22, 23, 24, . . . , such as the ordinary narrowing comb of a full-fashioned knitting machine. The comb may be operated manually but is preferably operated by a suitably timed mechanism for imparting to the narrowing points a sequence of movements in a coursewise direction along the needles 10—19 . . . and a sequence of movements transverse thereto and rectilineally of the length of the needles. Each coursewise shift of the narrowing points is followed by a vertical reciprocation of the narrowing points, and such reciprocations alternately lift a loop or loops from the needles and deposit the picked up loop or loops on other needles spaced coursewise from the needle or needles from which the loop or loops were lifted. Each alternate coursewise shift brings into coaction with a looped needle an additional narrowing point of the group.

As illustrated in line A of Fig. 6, the narrowing point 20 has been shifted leftward from beyond the active bank of needles 10 to 19 . . . into alignment with a looped needle 10 at or adjacent to a selvage of the fabric being knit. Upon alignment of the point 20 with the needle 10 as a result of this coursewise shift, the point 20 is dipped along the needle 10 within the fell loop a, and is then raised to lift the loop a clear of the needle 10. The comb on which the points are mounted is then shifted leftward coursewise a distance of one needle to bring the point 20, with the loop a thereon, into registration with the needle 11 and the point 20 is then dipped to deposit the loop a on the needle 11 over the loop b thereon, as indicated in row B of Fig. 6, so that if the needle 11 were removed, the loops a and b would be overlapped, as indicated in Fig. 8.

The point is raised to clear the loops on the needle 11, and the comb is again shifted coursewise leftward a distance of one needle to bring the point 20 into alignment with the looped needle 12 and to bring an additional point 21 into alignment with the double looped needle 11, as shown in line C of Fig. 6. The comb is then dipped to move the point 20 along the needle 12 within the loop c and to move the point 21 along the needle 11 within the loops a and b. The comb is then raised to cause the points 20 and 21 to pick up and lift the loops c, b, a, engaged thereby and clear the needles 11 and 12. The comb is then again shifted coursewise leftward a distance of one needle to bring points 20 and 21 into alignment with the respective needles 13 and 12, and the comb is dipped to deposit the loop c over the loop d on the needle 13 and to deposit the loops a and b on the vacant needle 12, as shown on line D of Fig. 6, so that if the needles 13 and 12 were removed, the overlapped loops c and d would form a gathered group in juxtaposition to the previously gathered group formed by the loops a and b, as indicated in Fig. 9.

The comb is again raised to free the points from the loops and shifted coursewise leftward a distance of one needle to bring the point 20 into alignment with the looped needle 14, to bring

the point 21 into alignment with the double looped needle 13, and to bring a point 22 into action in alignment with the double looped needle 12, as indicated in line E of Fig. 6. The comb is then dipped to move the points 20, 21 and 22 along the respective needles 14, 13 and 12, respectively, within the loop e, the loop group d, c and the loop group, b, a. The comb is then raised to cause the points 20, 21 and 22 to pick up the respective loops engaged thereby and lift them clear of the needles 14, 13 and 12. The comb is again shifted coursewise leftward a distance of one needle to bring the point 20 into alignment with the needle 15, to bring the point 21 into alignment with the needle 14, and to bring the point 22 into alignment with the needle 13. The comb is then dipped to move the points 20, 21 and 22 along the needles 14, 15 and 13 to deposit the loop e from the point 20 over the loop f on the needle 15, to deposit the loops d and c on the vacant needle 14, and to deposit the loops b, a on the vacant needle 13, as indicated in line F of Fig. 6, so that if the needles were removed the loops a to f would form three consecutive gathered groups of loops, as indicated in Fig. 10.

The comb is again raised to cause the points to clear the deposited loops and shifted coursewise leftward one needle to bring the point 20 into alignment with the looped needle 16, to bring the point 21 into alignment with the double looped needle 15, to bring the point 22 into alignment with the double looped needle 14, and to bring a point 23 into coactive position in alignment with the needle 13, as indicated in line G of Fig. 6. The comb is then dipped to move the points 20-23 lengthwise along the lengths of the respective needles 16-13 respectively within the loop g, the pairs of loops fe, dc and ba on such needles. The comb is then raised to cause the points to pick up the respective loops on the needles 16-13 and lift them clear of these needles. The comb is then again shifted coursewise leftward a distance of one needle to align the points 20-23 with the respective needles 17-14. The comb is then dipped to move the points 20-23 along the needles 17-14 and deposit the loop g from the point 20 over the loop h on the needle 17, to deposit the loops j, e from the point 21 on the vacant needle 16, to deposit the loops d, c from the point 22 on the vacant needle 15, and to deposit the loops b, a from the point 23 on the vacant needle 14, as indicated in line H of Fig. 6, so that if the needles were removed the fell course would contain consecutive groups of gathered loops hg, fe, dc and ba, as indicated in Fig. 11.

The comb is then again raised to cause the points to clear the deposited loops and shifted coursewise leftward a distance of one needle so as to bring the point 20 into alignment with the looped needle 18 and to bring the points 21-23 and an additional point 24 into action in alignment with the double looped needles 17-14 respectively. The comb is dipped to move the needles 20-24 downward along the needles 18-14 inclusive within the loops thereon. The comb is then raised to pick up the loop i from the needle 18, the loops h, g from the needle 17, the loops f, e from the needle 16, the loops d, c from the needle 15, and the loops b, a from the needle 14 and lift these loops above the needles. The comb is again shifted coursewise leftward a distance of one needle to bring the points 20-24 into alignment with the respective needles 19-15. The comb is dipped to move the points 20-24 downward along the needles 19 to 15 and deposit the loop i over the

loop j on the needle 19, to deposit the loops h, g on the needle 18, to deposit the loops f, e on the needle 17, to deposit the loops d, c on the needle 16 and to deposit the loops b, a on the needle 15, as indicated in line J of Fig. 6, so that if the needles were removed the fell course would contain juxtaposed pairs of loops composed respectively of gathered loops ji, hg, fe, dc, ba.

Narrowing is continued in the same manner until the course has been sufficiently narrowed to produce a row of narrowing marks extending coursewise across the wales substantially on a straight line normal to the wales and at a sharp angle to the selvage of the fabric, thereby fashioning the fabric in a manner resulting in a sharp bend or curvature in the wales adjacent to the selvage and a diminishing degree of curvature in the wales progressively remote from the selvage.

When the desired narrowing of the fell course has been effected by the coursewise shifting of the loops into a desired number of consecutive pairs, knitting is resumed by laying a yarn along the looped needles and moving the needles en masse to draw the new yarn through the loops and groups of loops on the needles so as to form a new and narrowed course 26 which holds the gathered loops together and the pairs or marks in juxtaposition to one another with their centers spaced a distance equal to the center-to-center spacing of the needles. While I have described in detail the narrowing of the fabric inward from one selvage only, it will be understood that the fabric will usually be narrowed inward in the same manner from both selvages simultaneously. The lines of marks thus formed simulate the "topping on" lines of two unit stockings but at a somewhat different angle.

Knitting may be then continued in any usual manner to any desired extent and a subsequent course, close to or remote from the course 25, may be narrowed in the same manner when additional narrowing and fashioning is desired or required. For example, courses 25 at the end of the heel widening may be narrowed across the major portions or substantially the entire widths of the heel reinforced sections of the blank, and the knitting of the foot continued in the usual manner after the course 26 has been knit until the extremity of the toe is reached. The fell course of loops forming a terminus of the toe section may be then narrowed inward from each selvage in the manner illustrated in Figs. 6 to 13, inclusive, and the narrowed course held in narrowed condition by a course 26 and one or more seaming courses or raveling courses.

In making two unit stockings, terminal courses 25b of heel tabs may be narrowed in the same manner to impart a curve to the bottom of the heel. The heel tabs are then topped on a footer 60 and the foot section knit in the usual manner until the extremity of the toe is reached, which may then be narrowed in the manner described. Either a single unit blank or a two unit blank formed as described may be seamed from toe to heel without the need of looping.

It will, of course, be understood that each of the loops a-j, inclusive, will ordinarily include yarns laid by the main carrier and reenforcing carrier, and that the term "loop" includes all the yarns laid by the main carrier and reenforcing carrier and initially looped around a needle.

Having described my invention, I claim:

1. A knit fabric stocking blank having loops forming wales and courses and having reenforced heel and sole sections divided from one another

by a row of narrowing marks extending coursewise from substantially the selvages to substantially the inner edges of the reenforced areas, each narrowing mark being composed of overlapped loops of adjacent wales aforesaid.

2. A knit fabric stocking blank having loops forming wales and courses and having heel and sole sections with substantially flat, unpuckered, areas divided from one another by rows of narrowing marks each composed of a loop group, each group being composed of loops of two wales only said rows extending coursewise in a substantially straight line normal to the adjacent wales, and said rows each containing at least three adjacent narrowing marks formed by loops of adjoining wales and extending transversely to the adjacent edges of the blank.

3. A knit fabric hosiery blank having loops forming wales and courses of a reinforced foot section, the loops in pairs of adjacent wales being overlapped coursewise on one another and forming at least three adjacent narrowing marks on each side of the fabric and in the same course and forming a substantially straight coursewise row of narrowing marks extending along a line substantially normal to the adjacent wales and across a major portion of the reinforced foot section, and a subsequent course interlooped with the foregoing course and comprising loops holding together the loops of the several overlapped groups and narrowing the fabric, the overlapped loops of the narrowed course and the loops of the subsequent course having substantially the same center to center spacing.

4. A method of narrowing a knit fabric having a course of loops on the needles of an en masse movable bank which comprises shifting a group of loop-engaging points coursewise step by step along said bank and into alignment with needles thereof, each successive coursewise movement being of uniform extent and bringing an additional needle into alignment with a point of said group, dipping and raising said points along needles aforesaid after each coursewise shift, lifting one or more loops from the needles by the points after alternate shifts and depositing loops on the needles from the points after intermediate shifts and increasing by the loops from two wales the number of loops lifted by the points after a shift over the number of loops deposited from the points after a previous shift.

5. A method of narrowing a knit fabric having a course of loops on needles of an en masse movable bank which comprises shifting a group of loop-engaging points coursewise step by step along said bank of needles, each of the successive coursewise shifts being of the same extent and aligning said points with needles aforesaid, dipping and raising said points along needles aforesaid after each coursewise shift to alternately lift loops from needles aforesaid and depositing the lifted loops on other needles aforesaid, the number of needles from which loops are successively lifted by the points varying in an arithmetical progression.

6. A method of narrowing a knit fabric which comprises knitting a web having loops forming wales and courses, shifting coursewise a loop of a course over an adjoining loop to form a narrowing mark, then shifting coursewise and in the same direction a loop adjacent to said narrowing mark over an adjoining loop to form a second narrowing mark and simultaneously shifting coursewise and to a similar extent the loops forming the first narrowing mark, and so on suc-

cessively shifting coursewise a loop adjacent to a last formed narrowing mark over an adjacent loop to form an additional narrowing mark and simultaneously shifting coursewise in the same direction and to a similar extent the loops constituting the previously formed narrowing marks, and drawing a new course of loops simultaneously through the pairs of loops forming said narrowing marks to position the same and substantially narrow the fabric.

7. A knit fabric having loops forming wales and courses and including a course containing adjacent groups of overlapped loops forming at least three adjoining narrowing marks on each side of the fabric, each group including loops of two wales only, and a course interlooped with said last-named course and comprising loops spaced center-to-center substantially the same distance as the original center-to-center spacing of said first-named loops before the overlapping thereof and said second-named loops holding together said groups so as to substantially halve the width of the fabric section immediately following the overlapped loops as compared with the width of the fabric section immediately preceding the overlapped loops.

8. In a method of narrowing a knit fabric having a course of loops on adjacent equidistant needles, the steps which comprise moving a group of loop-engaging points coursewise in uniform, successive steps and into alignment with needles aforesaid, raising and lowering said points to lift and deposit loops aforesaid, said points being devoid of loops during alternate coursewise movements thereof and carrying loops coursewise during intermediate coursewise movements thereof to group loops aforesaid, and drawing yarn through adjacent groups to form loops spaced center-to-center substantially the same distance as the center-to-center spacing of the first-named loops before the coursewise shifting thereof.

9. The method which consists in knitting a flat stocking blank to include a half heel portion at each side thereof, progressively transferring a group of knitted stitches inwardly from the outer selvage edge of each half heel portion to the extent of one needle in each of a plurality of successive transfer steps in a single course of stitches in each half heel portion to foreshorten said course and produce a puckering of the fabric therein, and knitting a course of stitches to said foreshortened course.

10. The method of narrowing a knitted fabric while needle loops of a single course are carried by a series of needles, which comprises delivering the loop on the outside needle inwardly onto the next inwardly positioned needle to form a double loop thereon, simultaneously delivering the outermost single loop and the said double loop inwardly by one needle to form two double loops, simultaneously delivering the outermost single loop and all of the double loops inwardly each by one needle, and repeating the same action until the fabric has been narrowed to the desired extent.

11. In a knitting machine having a series of needles for carrying yarn loops and width-changing combs for transferring loops laterally from needle to needle, the method of changing the width of the knitted fabric between successive knitting courses, which comprises moving said combs laterally in cycles and repeating such cycles a plurality of times, each cycle comprising two movements of each comb in one direction all of said movements being of equal extents, and

causing said combs when moving in one only of the two times in each cycle to transfer loops from needle to needle.

12. A method of narrowing a knit fabric having a course of loops on the needles of an en masse movable bank which comprises shifting a group of loop engaging points coursewise step by step the distance of one needle at a time along said bank and into alignment with needles thereof, each successive coursewise movement bringing a point aforesaid into alignment with an additional needle, dipping and raising said points along needles aforesaid after each coursewise shift, said points being free of loops during certain of their coursewise shifts and carrying loops during other of their coursewise shifts.

13. In the knitting of fabric on a knitting machine having a series of needles for carrying yarn loops and width changing combs for transferring loops laterally from needle to needle, the method of changing the width of the knitted fabric between successive knitting courses which com-

prises moving said combs laterally in cycles and repeating such cycles a plurality of times, each cycle comprising two movements of each comb in one direction, all of said movements being of equal extents, and causing said combs when moving in the first only of the two times in each cycle to transfer loops from needle to needle.
